UNITED STATES PATENT OFFICE.

WILSON ROSEBRAUGH, OF NEWARK, OHIO, ASSIGNOR TO HOLOPHANE COMPANY, INC., OF NEW YORK, N. Y., A CORPORATION OF NEW YORK.

COMBINED SHADE AND REFLECTOR.

Application filed August 9, 1927. Serial No. 211,666.

The object of the present invention is the manufacture of a combined shade, reflector, and holder, in which a reflector cover fits closely about one portion of the bulb, and 5 is provided with means for supporting a shade or screen. This shade normally screens the uncovered part of the bulb and is adapted to receive a combined beam consisting of light reflected from the reflector 10 as well as direct light from the lamp.

The present invention contemplates a reflector, shade and holder directly mounted on the lamp bulb and capable of permitting a movement of the shade in all directions so 15 that it may be placed in any desired position about the lamp bulb and the light directed as desired.

The invention is particularly directed toward the type of reflector and shade designed to be directly supported from incandescent lamps. A shade or screen of glass or other translucent material is directly supported on an opaque reflector adjacent to an incandescent lamp so as to obtain a beam of 25 light in the desired direction or a desired color. Under many conditions it is also desirable to obtain an asymmetric light beam whose axis may be adjusted to a variety of angles and which may be turned about this 30 axis to obtain the desired lighting effects.

One of the objects of the invention is to provide a reflecting cup about the bulb of the incandescent lamp so as to control the light distribution.

The parts are so arranged that the shade whether of disc, lens, or refractor form, may be moved about the lamp bulb in a variety of positions so as to direct the axis of the beam in the desired direction irrespective of 40 the angle of the lamp socket. Where an asymmetric distributing lens is used, the lens may be turned so that the maximum light distribution is brought into the desired plane.

A further object of the present invention is to provide a shade holder more especially of the class above referred to wherein the incandescent lamp may be passed through the shade holder parts and swung to position to 45 secure the shade holder on the lamp bulb without the use of tools or the connecting and disconnecting any of the parts.

The accompanying drawings show, for purposes of illustration, one of the many 55 possible embodiments in which the present

invention may take form, it being understood that the drawings are illustrative of the invention rather than limiting the same.

In these drawings:

Figure 1 is a side view of an incandescent 60 lamp, a reflector, a shade and support, showing the adjustment of reflector, shade and movable supporting member in the plane of the longitudinal axis of the lamp;

Figure 2 is a sectional view on the broken 65 line 2-2 of Figure 1;

Figure 3 is a side view of the parts showing the position assumed when the lamp is being inserted into the shade supporting member or being removed from it; and 70

Figures 4^a and 4^b are fragmentary views of an asymmetric cup suitable for use in the present invention.

The essential parts of the invention are a reflecting cap, a shade and various supporting parts herein described. The reflecting cap 22 may conveniently be in the form of 75 an aluminum stamping and is found to redistribute the light and direct it out through the lower side of the lamp and toward the shade 10 when the parts are in the position indicated in full lines in Figure 1. A band 26 which may conveniently be in the form of a wire member is attached to the rear ends or tips 27 of the cap 22. This band is 80 adapted to pass about the neck of the bulb as indicated at 25.

The shade as indicated at 10 of the drawings may be of any desired form. It is as here shown in the form of a glass lens having 90 a central aperture 11. An apertured disk 12 or other form of packing, is placed in the aperture in the lens, as indicated. Two small metal washers 13 and 14 are placed against the sides of the glass disk 95 and a clamping bolt 15 passes through the packing 12 and washers 13 and 14. A nut 16 is threaded onto the bolt for clamping these parts together. A yoke 17 has a threaded hole 17' to receive the bolt 15, and 100 a coiled spring 18 is carried between the head of the bolt 15 and the washer 13 so that the yoke, screw, washers and lens may be also secured in place by tightening up the nut 16.

The yoke 17 may be made out of a bent 105 piece of sheet metal and is provided at its upper ends 19 and 20 with pivot pins 21 to support a cover member or cap 22 of spherical shape and adapted to engage, as indi- 110

cated in the drawings, about one-half of the bulb portion 23 of the incandescent lamp 24, and to extend a short distance beyond the equator of the bulb toward the neck 25 of the bulb.

In placing the shade holder in the lamp bulb, the parts are brought to the position indicated in full lines in Figure 3. The base of the lamp is passed upwardly between the band 26 and the cap 22, which is cut away in its edges as indicated at 28 to accommodate the neck of the lamp. The lamp is then moved in a clockwise direction to bring the bulb in against the reflecting cap whereupon the cap 22 and band 26 will swing or pivot on pins 19 and 20 toward the dot and dash line position indicated in Figure 1 so as to bring the spring 18 against the surface of the lamp bulb. This spring presses against a large area of the lamp bulb and securely holds the shade holder on the lamp in all positions into which it may be brought. The band 26 prevents the spring from forcing the lamp out of the holder when the spring is near the tip of the bulb. When one desires to remove the shade holder from the lamp, it is merely necessary to bring the shade to the dot and dash lines of Figure 1, whereupon the spring 18 will engage the edge 29 of the cap 22 so that the bulb is released and the lamp may be swung down to the dotted line position shown in Figure 3.

From the foregoing, it will be apparent that the present form of shade holder is well suited for carrying shades directly from incandescent lamps and one wherein the shade may be very securely fastened on the lamp in any desired position. The reflecting cover 22 reflects a considerable portion of the light back toward the lamp center and this reflected light is added to the direct light from the lamp and therefore increases the light which falls on the shade. This increased light is available throughout a wide range of adjustment of the shade. The shade acts as a screen for the direct and reflected light, and when in the form of a refractor may redirect substantially all the light from the lamp into desired directions.

It will be noted that the shade holder may be swung in the plane of the axis of the lamp bulb through about 90°, as indicated in Figure 1, also that the axis, shade holder and shade may be bodily rotated about the axis of the lamp bulb to bring it to any desired position. Where one desires an asymmetric distribution of light in the emitted beam, an asymmetric refracting cup, such as shown, may be used. Such a refractor may have a series of circular prisms 30 on one side and parallel refracting prisms 31 on the other side for concentrating the beam collected by the prisms 30. Turning the refractor from the position of Figure 4^a to

that of Figure 4^b will vary the light distribution in the desired manner. This refractor is more particularly described in application Serial Number 701,970, filed March 26, 1924. It may be twisted about on the supporting pin or bolt 15 to give the desired distribution of light and may be readily removed from this pin whenever desired.

The device is especially applicable to installations where it is not practical to install elaborate or large reflector shade types, and is especially useful in cove or window lighting, or as a directional unit, part of the bulb equipment, in larger installations embodying other directing means.

I claim:

1. A combined reflector and shade for incandescent lamps, comprising a reflecting bulb cover member adapted to closely engage a portion of the bulb surface, a shade normally lying in front of the uncovered part of the bulb, and means for pivotally fastening the shade to the reflector to permit a movement of the shade to screen a desired portion of reflected or direct rays from the bulb.

2. A combined reflector and shade for incandescent lamps, comprising a reflecting bulb cover member adapted to closely engage a portion of the bulb surface, a shade normally lying in front of the uncovered part of the bulb, means for pivotally fastening the shade to the reflector to permit a movement of the shade to screen a desired portion of reflected or direct rays from the bulb, and a yieldable member movable with the shade for holding the shade and reflecting cover member on the lamp bulb.

3. In combination, an incandescent lamp, a reflecting cover member closely engaging a substantial portion of the bulb surface to reflect the light back toward the center of the lamp, a shade, and means for pivoting the shade from the reflecting cover member so that it may be swung about the uncovered portion of the bulb to receive direct rays from the light source and a substantial portion of the rays reflected by the cover member.

4. In combination, an incandescent lamp, a reflecting cover member closely engaging a substantial portion of the bulb surface to reflect the light back toward the center of the lamp, a shade, and means for pivoting the shade from the reflecting cover member on an axis transverse of the centre of the light source so that it may be swung about the uncovered portion of the bulb to receive direct rays from the light source and a substantial portion of the rays reflected by the cover member.

5. In combination, an incandescent lamp, a reflecting cover member closely engaging a substantial portion of the bulb surface to

reflect the light back toward the center of the lamp, a refractor, and means for pivoting the refractor from the reflecting cover member on an axis transverse of the centre of the 5 light source so that it may be swung about the uncovered portion of the bulb to receive direct rays from the light source and a substantial portion of the rays reflected by the cover member, the refractor being at all 10 times the same distance from the light source.

6. A shade holder for supporting shades and the like from incandescent lamps, comprising, a member engageable with a part of the bulb portion of the lamp, a shade carrying 15 yoke pivotally carried by said member, and a spring carried by the yoke and engageable with said bulb, opposite the part engaged by the member, said spring pressing the bulb toward the member to hold the parts 20 in place on the lamp.

7. A combined reflector and shade for incandescent lamps, comprising, a reflecting cap engageable with a part of the bulb portion of the lamp, a shade carrying yoke 25 pivotally carried by said cap, a spring carried by the yoke and engageable with said bulb opposite the part engaged by the member, said spring pressing the bulb toward the member to hold the parts in place on the 30 bulb, and a shade carried by the yoke opposite the reflecting cap.

8. A combined reflector and shade for incandescent lamps, comprising, a shade supporting yoke having an outwardly projecting 35 pin at the center of the yoke for attachment of the shade, the yoke being adapted to embrace the bulb of the lamp, a reflection bulb cover carried by the ends of the yoke and adapted to fit the bulb portion of the lamp, a band connected to the side edges 40 of the cover, and a spring carried by the yoke and engageable with the bulb to press it against the cover.

9. A shade holder for supporting shades 45 and the like from incandescent lamps, comprising, a bulb cover member shaped to closely engage substantially one half the surface of the bulb portion of the lamp and extending toward the neck of the lamp, a band 50 connected across the neck engaging end of the cover member and adapted to pass about the neck of the lamp, a shade carrying yoke pivotally carried by the cover member on an axis transverse of the lamp axis, and a spring 55 carried by the yoke for pressing against the bulb to hold it in the cover member.

10. A combined reflector and shade for incandescent lamps, comprising, a reflecting bulb cover member adapted to closely engage 60 a portion of the surface of the bulb portion of the lamp and extending toward the neck of the lamp, a band connected across the neck engaging end of the cover member, and adapted to pass about the neck of the lamp, a shade carrying yoke pivotally carried by the 65

cover member and being capable of being swung about an axis transverse of the lamp axis, a spring carried by the yoke for pressing against the bulb to hold it in the cover member, a shade supporting pin carried by 70 the yoke, and a shade pivotally mounted on the pin.

11. A shade holder for supporting shades and the like from incandescent lamps, comprising, two members between which the base 75 and neck portions of the lamp may be freely passed, a shade carrying yoke pivotally carried by one of the members and passing about the bulb portion of the lamp, and a spring carried by the yoke and engaging the 80 bulb to force it against said members and secure the same on the bulb.

12. A shade holder for supporting shades and the like from incandescent lamps comprising, two members between which the 85 base and neck portions of the lamp may be freely passed, one of said members being in the form of a reflector, a shade carrying yoke pivotally carried by said reflector and passing about the bulb portion of the lamp, 90 and a spring carried by the yoke and engaging the bulb to force it against the reflector and secure the same on the bulb.

13. A shade holder for supporting shades and the like from incandescent lamps, comprising, a stamping of suitable shape to engage a substantial portion of the surface of a lamp bulb from the tip to beyond the center of the bulb, a band attached to opposite sides of the stamping and adapted to 100 pass about the neck of the bulb, a yoke pivoted to the sides of the stamping with the pivotal center at substantially the center of the bulb, said yoke being capable of being swung on its pivot about the bulb, and a 105 coiled spring carried by the yoke and engageable with the lamp bulb to hold it against the stamping as the yoke is moved about.

14. A shade holder for supporting shades 110 and the like from incandescent lamps, comprising, a stamping of suitable shape to engage a substantial portion of the surface of a lamp bulb from the tip to beyond the center of the bulb, a band attached to opposite sides of the stamping and adapted to 115 pass about the neck of the bulb, a yoke pivoted to the sides of the stamping with the pivotal center at substantially the center of the bulb, said yoke being capable of being 120 swung on its pivot about the bulb, and a coiled spring carried by the yoke and engageable with the lamp bulb to hold it against the stamping as the yoke is moved about, the stamping having an edge against 125 which the spring is brought to limit the swinging of the yoke to positions in which the spring may hold the parts in place.

15. A shade holder for supporting shades 130 and the like from incandescent lamps, com-

prising, a stamping of suitable shape to engage a substantial portion of the surface of a lamp bulb from the tip to beyond the center of the bulb, a band attached to opposite sides of the stamping and adapted to pass about the neck of the bulb, a yoke pivoted to the sides of the stamping with the pivotal center at substantially the center of the bulb, said yoke being capable of being swung on its pivot about the bulb, and a coiled spring carried by the yoke and engageable with the lamp bulb to hold it against the stamping as the yoke is moved about, the stamping having an edge against which the spring may be brought, said edge acting as an abutment when the bulb is to be removed from the shade holder.

16. A shade holder for supporting shades and the like from incandescent lamps, comprising, two members between which the base and neck portions of the lamps may be freely passed, a shade carrying yoke pivotally carried by one of the members and passing about the bulb portion of the lamp, a shade holding bolt threaded through the yoke, and a spring carried between the head of the bolt and the yoke engaging the bulb to force it against said members and secure the same on the bulb.

Signed at Newark, in the county of Licking and State of Ohio, this 6th day of August, 1927.

WILSON ROSEBRAUGH.
